UNITED STATES PATENT OFFICE.

EMILE LOUIS ALLIÉ, OF PARIS, FRANCE.

SPRINKLING-STOPPER.

1,257,173.

Specification of Letters Patent. Patented Feb. 19, 1918.

Application filed May 27, 1914. Serial No. 841,231.

To all whom it may concern:

Be it known that I, EMILE LOUIS ALLIÉ, of 38 Rue de la Chine, in the city of Paris, Republic of France, have invented Improvements Relating to Sprinkling-Stoppers, of which the following is a full, clear, and exact description.

This invention has for its object a sprinkling stopper which cannot be tampered with, said stopper being designed more particularly for bottles containing liquid perfumes or other analogous products.

This stopper, which consists of a floating valve and a ball forming a counterweight, placed in a chamber in the interior of the stopper and arranged in such a manner that, if the bottle be motionless, in any position, the float obstructs the outlet orifice and the liquid cannot escape, is characterized by the fact that it is internally provided with a screen having for its object to prevent any fraudulent refilling of the bottle, and that it is combined in such a manner that the various parts which constitute it can be assembled by flanging or hooking in a single operation.

The invention is shown, by way of example only, in the annexed drawing, wherein:

Figure 1 is a vertical section of the stopper.

Fig. 2 is a plan view of the valve.

Fig. 3 is an underside view of the conical cap.

As will be seen on the drawing, the stopper is constituted by three main parts: a hollow cylindrical body *a*, an upper conical part *b* or outer part and an inner conical cap *c*.

Within the cylindrical body *a* are arranged a valve *d* and a ball *e*.

The upper part *b*, which is integral with a cylindrical hood *f* adapted to fit upon the neck of the bottle, is provided with a circular shoulder *g* on which fits the collar *h* of the conical cap *c*.

The wall of said conical cap is provided with a number of slots *i* adapted to allow the passage of the liquid and to prevent any insertion of a wire in the inner chamber of the cylindrical body *a*, by reason of the arrangement of tongues *j* projecting in the chamber *k*.

The cylindrical body has, at its upper part, a flange *l* fitting on the collar *h*.

The three parts of the stopper are finally assembled by the flanging of an annular

crown or of fastening devices *m* integral with the part *b*.

The valve *d*, held upon its seat *o* by the ball *e*, is preferably made of india rubber and is externally provided with ribs or wings *n*, allowing it to slide in the lower part of the cylindrical body, without opposing the passage of the liquid.

The operation of this stopper is as follows:

As soon as the bottle has been slightly inclined, the ball, by reason of the conical incline of the cap, places itself at the bottom of the latter and the valve is freed. At the same time the external air, passing through the chamber *k* and the orifices *i*, fills the inner chamber and from thence passing around the valve via the free space left between the ribs *n*, it enters the interior of the bottle through the circular hole formed at the bottom of the stopper. The liquid then flowing to the stopper passes into the hollow space in the valve located opposite the circular hole; the valve is thus slightly raised and provides a passage for the liquid which flowing through the empty space between the valve *d* and the internal wall of the chamber, passes through the orifices *i* in order to spread itself in the chamber *k* whence it reaches the exterior.

It will be seen that if the bottle be left motionless, only a very small quantity of liquid would flow out; this would be promoted by the capillarity, so that the liquid would immediately intercept any fresh entrance of air; but by imparting to the bottle slight shocks from top to bottom like ordinary sprinkling bottles, a succession of intermittent flows can be obtained which would ultimately be converted into an almost continuous jet.

The conical cap *c* can be surmounted by a rod or cylindrical column bearing a certain number of longitudinal grooves and fitting into the chamber *k*; one will thus prevent the introduction into the interior of the stopper, of an iron wire or other similar implement, for the purpose of raising the valve and thus fraudulently filling the bottle with a liquid other than that which it should normally contain.

Finally, the stopper can be provided with a cap in order to obviate any entrance of dust and to prevent the evaporation of the liquid.

This stopper, which is preferably made of

tin or any other suitable metal, presents the great advantage of being very easily mounted. In fact, when the three parts which form it have been assembled in the desired order, it is only necessary, in order to unite them definitely, to bezel the circular flange *m* on to the flange *l*. There is thus obtained a stopper in a single piece which fixes itself in place by bezeling its exterior circumferential part *f* on to the bottle-neck or on to the collar around the mouth of the bottle.

It is obvious that the arrangements are only given by way of example; the forms, dimensions, materials and detail arrangements can be varied in all cases without thereby departing from the nature of the invention.

Claims:

1. A sprinkling stopper of the character described, comprising a hollow conical member having a cylindrical hood for securing it to a bottle, a second conical member secured in the first member, said member being slotted and having tongues projecting from its apex over the slots thereof, a hollow cylindrical body having a reduced lower end and secured to the first named conical member below the second member and forming therewith a chamber, a ball in

said chamber, and an elongated valve in the reduced end of the body and provided with ribs.

2. A sprinkling stopper of the character described, comprising an upper conical member having an internal shoulder and a cylindrical hood at its lower end, a conical slotted member extending into the first member and having a flange engaging the shoulder thereof, the slotted conical member having tongues projecting from its apex, a hollow cylindrical member having a reduced portion at its lower end and a flange at its upper end engaging the flange of the slotted member, means for securing the flanges of the said members in position, an elongated valve in the reduced portion of the cylindrical member and having ribs, and a ball in the chamber formed by the upper larger part of the cylindrical member and the slotted conical member.

The foregoing specification of my improvements relating to sprinkling stoppers signed by me this 12th day of May, 1914.

Paris, France.

EMILE LOUIS ALLIÉ.
